(57) **CLAIM**

The ornamental design for rocker switch, as shown and described.

DESCRIPTION

FIG. 1 is a front perspective view of the rocker switch in accordance with my invention;

FIG. 2 is a rear perspective view thereof;

FIG. 3 is a rear view thereof;

FIG. 4 is a front view thereof.

FIG. 5 is a right side view thereof.

FIG. 6 is a left side view thereof; and,

FIG. 7 is a top view thereof.

The bottom view of the rocker switch is not shown and is not part of the claimed invention.
